US0D1097173S

(12) **United States Design Patent** (10) Patent No.: **US D1,097,173 S**
(45) Date of Patent: ** Oct. 7, 2025

(54) **BREAST ENLARGEMENT DEVICE**

(71) Applicant: **Yujie Dai**, Zhongxiang (CN)

(72) Inventor: **Yujie Dai**, Zhongxiang (CN)

(**) Term: **15 Years**

(21) Appl. No.: **29/980,631**

(22) Filed: **Dec. 26, 2024**

(30) **Foreign Application Priority Data**

Nov. 11, 2024 (CN) 202430712680.4

(51) **LOC (15) Cl.** **24-04**

(52) **U.S. Cl.**

USPC **D24/190**

(57) **CLAIM**

The ornamental design for a breast enlargement device, as shown and described.

DESCRIPTION

FIG. 1 is a front, right and top perspective view of a breast enlargement device, showing my new design;

FIG. 2 is a perspective view thereof;

FIG. 3 is a perspective view thereof;

FIG. 4 is a front view thereof;

FIG. 5 is a rear view thereof;

FIG. 6 is a left side view thereof;

FIG. 7 is a right side view thereof;

FIG. 8 is a top plan view thereof; and,

FIG. 9 is a bottom plan view thereof.

1 Claim, 9 Drawing Sheets
